DESIGN FOR A BOLT OPERATING HANDLE FOR FIREARMS

Harold F. Mossberg, New Haven, Conn., assignor
to O. F. Mossberg & Sons, Inc., New Haven,
Conn., a corporation of Connecticut

Application March 22, 1944, Serial No. 112,996

Term of patent 14 years

(Cl. D30—1)

To all whom it may concern:

Be it known that I, Harold F. Mossberg, a citizen of the United States, residing in New Haven, in the county of New Haven and State of Connecticut, have invented a new, original, and ornamental Design for a Bolt Operating Handle for Firearms, of which the following is a specification, reference being had to the accompanying drawing, forming a part thereof, in which:

Figure 1 is a top plan view of a bolt operating handle for firearms showing my new design;

Figure 2 is a side elevational view of the same.
In the bolt operating handle of this design, both sides of the bolt engaging loop are similar.

I claim:

The ornamental design for a bolt operating handle for firearms, substantially as shown and described.

HAROLD F. MOSSBERG.
